[57] CLAIM

The ornamental design for a novelty baseball cap, as shown and described.

DESCRIPTION

FIG. 1 is a left side elevational view of the novelty baseball cap of the present invention;

FIG. 2 is a right side elevational view of the novelty baseball cap of FIG. 1;

FIG. 3 is a rear elevational view of the novelty baseball cap of FIG. 1;

FIG. 4 is a front elevational view of the novelty baseball cap of FIG. 1;

FIG. 5 is a top plan view of the novelty baseball cap of FIG. 1; and,

FIG. 6 is a bottom plan view of the novelty baseball cap of FIG. 1.

The broken line showing of the logo patches in FIGS. 1, 2, and 4 is for illustrative purposes only and form no part of the claimed design.
